Carbon — 0.035 Max.

Manganese — 1-4.0

Silicon — 0.20 Max.

Phosphorus — 0.020 Max.

Sulfur — 0.005 Max.

Chromium — 19.0 —26.0

Nickel — 32.5-38

Molybdenum — 2-9

Copper — 3.0-4.0

Columbium — 0.35 Max.

Cerium — 0.01 Max.

Boron — 0.0035 Max.

ABSTRACT

Weld-filler material particularly useful in providing enhanced freedom from weld cracking in fully austenitic Fe—Ni—Cr—Mo—Cu material in which the elements P, Cb, Ce+La, C, Si, S, N and O are controlled to low levels and in which the level of manganese is increased to at least 1% and preferably to at least 1.5%. The weld-filler material in weight percent contains:

the balance being iron and in which cerium includes cerium plus lanthanum or misch metal.
